FIREARM

Harold F. Mossberg, New Haven, Conn., assignor
to O. F. Mossberg & Sons, Inc., New Haven,
Conn., a corporation of Connecticut

Application April 3, 1940, Serial No. 327,591

3 Claims. (Cl. 42—16)

This invention relates to improvements in firearms and more particularly to improvements in the loading and firing means, or actions, of relatively small calibre firearms.

Certain of the features and principles of this invention are adapted for use in firearms of the automatic type wherein the bolt is automatically retracted by the recoil caused by firing a cartridge, to automatically eject the empty shell, and to set the action into subsequent firing condition. These, with other features, are especially adapted for use in guns, such as a single shot automatic rifle, wherein only one cartridge is inserted at a time, and in accordance with the features of this invention the action is automatically set in firing condition, ejects the empty shell, and has its parts positioned whereby a fresh cartridge may be readily inserted into the chamber.

One object of this invention is to provide in a firearm of the above type, a recoil actuated bolt adapted to cooperate with a swingable loading platform to insure that the latter is in fully closed position when the firearm is fired.

Still another object of this invention is to provide means to catch the bolt, of a bolt action firearm, as it is retracted by the recoil to prevent the firearm being accidentally fired before it has again been properly loaded.

A still further object of this invention is to provide an improved form of firearm which will be relatively inexpensive to manufacture, simple in construction, of pleasing appearance, and which is very efficient and durable in use.

With these and other objects in view, which will appear as the description proceeds, there has been illustrated in the accompanying drawings one form in which the invention may be conveniently embodied in practice.

In the drawings, wherein like reference numerals designate like parts throughout the several views:

Figure 1 is a side elevational view of a small calibre firearm embodying the features and principles of this invention;

Figure 2 is an enlarged side elevational view of the receiver, trigger, and a portion of the barrel, removed from the firearm shown in Figure 1, with the parts associated therewith;

Figure 3 is a rear end view of the parts shown in Figure 2;

Figure 4 is a cross-sectional view taken on the line 4—4 of Figure 2;

Figure 5 is a broken sectional view taken on the line 5—5 of Figure 4;

Figures 6, 7, and 8 are longitudinal sectional

views through the receiver showing the action in three different operative positions;

Figure 9 is a broken sectional view showing the bolt locking means in operative position; and

Figure 10 is a cross-sectional view taken on the line 10—10 of Figure 9.

The firearm selected to illustrate the features and principles of this invention comprises a combined stock and forearm 10, 11 respectively, a trigger guard 12, a barrel 13, which is secured into the forward end of a hollow cylindrical receiver 14 and with it is releasably secured to the forearm 11 by the usual take-down screw 15, which is screw-threaded into a post 16, fastened to and extending downwardly from the receiver 14. Suitable sights 17 and 18 may be provided and these are mounted respectively upon the front and rear ends of the barrel 13. A suitable vertically disposed slot 19 is provided, in this instance, in the forearm 11 leading from the bottom of the forearm upwardly to the underside of the receiver 14, through which ejected shells may fall. The barrel 13, as is usual, has a chamber 21 at its breech end 22 to receive a cartridge 23 which, in this instance, is slid into the chamber 21 from a loading platform 24.

The loading platform 24 is disposed in an opening 25 formed in the upper forward section of the receiver 14 and is hinged, at its rear end, 30 to the receiver 14 by a transverse pin 26. The forward portion 27 of the platform is considerably thicker than the wall of the receiver 14 and extends downwardly into its bore 28 and has, at this point, a flat surface 29. A short tongue 31 extends beyond the front end of the forward portion 27, of the platform 24, to underlie the wall of the receiver 14 to form a stop, to prevent the platform 24 swinging upwardly out of the opening 25. The platform, at its outer, or top, surface is curved, the curvature preferably being the same as that of the periphery of the receiver 14. A shallow groove 32, arcuate in cross-section, is provided in the top surface of the platform 24 in which a cartridge 23 may be placed 45 in preparation for loading it into the gun. The forward end of the groove 32 curves slightly upwardly at the forward end 27 of the platform 24 to assist in aligning the cartridge with, and in guiding it into, the chamber 21.

50 The platform 24 is adapted to be swung inwardly into the bore 28 of the receiver 14, as shown in dotted lines in Figure 5, to present the upwardly curved forward end 33 of the groove 32 in line with the chamber 21, by pressure applied thereto through a cartridge held in the

user's fingers, to overcome the tension of a spring 34, which spring tends to maintain the platform 24 upwardly into the opening 25 to close it. The spring 34, in this instance, is coiled about the pivot pin 26 with one of its ends, 35, extending rearwardly from the pin 26 to engage the underside of the receiver wall to the rear of the pin 26. The forward end portion 36, of the spring 34, is extended forwardly to engage the underside of the platform 24 within a longitudinal groove 37 formed therein along the entire length of its forward portion 27. The spring end portion 36 is extended forwardly beneath the portion 27 of the platform 24 and is bent downwardly to dispose its end 39 directly to the rear of the chamber 21, in the barrel 13, and therefore in back of the rear end of a cartridge 23 in said chamber 21 to prevent the cartridge accidentally dropping out of said chamber. When the platform 24 is in depressed position, as shown in dotted lines in Figure 5, the spring end portion 36 is adapted to be received in the groove 37.

The cartridge 23, when in the chamber 21, is adapted to be engaged and fired by a cylindrical combined bolt and firing pin 40, the forward end of the bolt 40 being counterbored, as at 41, to receive the primer head 42 of the cartridge 23, and having a primer striking lug 43 protruding therefrom disposed in position to strike the head 42 and fire the cartridge. A cartridge shell extractor finger 44 is secured to the bolt 40 by a screw 45 and extends forwardly along the bolt in a groove 46 provided therefor. A hooked end 47 on the finger 44 is adapted to snap under the head 42 of the cartridge shell to draw it out of the chamber 21 when the bolt 40 is retracted and to permit it to drop through an opening 48 formed in the receiver 14, which opening 48 is in line with the opening 19 provided in the forearm 11. A flat surface 49, formed on the periphery of the bolt 40, by cutting out a portion thereof, is provided at the top forward portion of the bolt 40 to slidably engage the flat underside surface 29 of the platform 24 when the bolt is in forward position in the receiver 14, to securely lock the platform up into the opening 25 to securely close and seal it. In this instance, the spring end 36 is also forced upwardly by the bolt 40 into the groove 37.

The bolt 40 is constantly under the tension of a coiled spring 51 which is disposed in a bore 52 provided in the rear end of the bolt 40 for this purpose. The spring 51 extends out of the bore 52 and about a rod 53 extending forwardly from a removable plug 54 disposed in the rear end of the receiver 14. The spring 51 constantly reacts between the plug 54 and the bottom of the bore 52 in the bolt 40 to urge the bolt forwardly. The plug 54 is provided with diametrically opposite outwardly extending lugs 55 and 56, adapted to enter slots 57 and 58 respectively provided in the rear end of the receiver 14, and to be rotated with the plug 54 to dispose them in forwardly facing slots 59 and 61 in the receiver, to lock the plug 54 thereto, peripherally formed slots 62 connecting the slots 57, 59 and 58, 61 for this purpose. One of the slots 57, 58, in this instance, slot 58, is extended forwardly in the receiver 14 to receive and guide the shank 63 of a screw 64, screw-threaded into the side of the bolt 40 adjacent its rear end (see Figures 9 and 10). A thumb, or finger, engaging knurled sleeve 65 is rotatably mounted on the screw 64, the head 66 of the screw lying in a counterbore

67 in the sleeve 65 to prevent the sleeve slipping therefrom. The counterbore 67 is of sufficient depth to permit the sleeve 65 the required amount of sliding movement, axially on the screw 64, to permit its inner end 68 to enter a circular enlargement 69 of the slot 58. The position of the circular enlargement 69 in respect to the bolt 40 is such that, when the bolt 40 is substantially in its fully retracted position, the inner sleeve end 68 may be readily entered therein to lock the bolt 40 in such fully retracted position.

The bolt 40, in this instance, is provided upon its bottom surface with a sear shoulder 71 and a catch shoulder 72, the former being spaced forwardly from the latter, which latter one, 72, is formed in the bolt 40 adjacent its rear end. A trigger 73 is provided, and has a finger engaging portion 74 which is extended downwardly into an opening 75 provided in the trigger guard 12 for this purpose. The trigger 73 is pivoted to the receiver 14 by a transverse pin 76, and has an integral arm 77 extending forwardly of the pivot pin 76. A sear hook 78 is provided on the forward end of the arm 77, and is adapted to engage the sear shoulder 71 to releasably hold the bolt 40 in retracted firing position. A transverse pin 79 extending through the arm 77 limits the upward swinging movement of the sear hook 78, which is constantly under the urge of a spring pressed plunger 81 reacting against the underside of the receiver by a spring 82, disposed in a hole 83 provided in a lug 84 extending rearwardly from the trigger 73.

When the cartridge 23 has been fired, by the release of the bolt 40 to permit it to be rapidly moved forwardly by the spring 51 and cause the lug 43 to strike the primer head 42 of the cartridge, by pressing rearwardly upon the trigger finger portion 74 to release the sear hook 78 from the sear shoulder 71, the recoil action of the explosion automatically retracts the bolt 40 to a rearward position in the receiver 14. This action is extremely rapid and, should the trigger finger portion 74 not be released by the user's finger as soon as pressed, the bolt 40 will again move forwardly to no avail, as no cartridge 23 is in firing position in the chamber 21. In such an instance no recoil action would take place and the bolt would have to be retracted into firing position by hand. To obviate this possibility, a catch 85 is provided to automatically catch the bolt 40 when it reaches its full recoil retracted position, as shown in Figure 7, after a cartridge is fired.

The catch 85, in this instance, is in the form of an inverted U-shaped member, having a horizontally disposed top portion 86 from which depend side arms 87 and 88 which straddle the trigger 73. The catch 85 is pivoted to the trigger 73 by a transverse pin 89, which passes through the lower ends of the arms 87 and 88 adjacent the lower front edge 90 of the catch 85. A spring pressed plunger 91 carried by the trigger 73 and urged upwardly by a spring 92, is disposed in a hole 93 provided in the upper surface of the trigger 73, and engages the underside of the top portion 86 of the catch 85 to urge the front upper edge 94 of the catch 85 into engagement with a rearwardly facing shoulder 95 provided on the trigger 73 for this purpose.

When the bolt 40 is rapidly retracted by the recoil action from its forward position, shown in Figure 6, it will freely slide past the sear hook 78 as this is held down by the trigger being

pressed by the user's finger. The bolt 40 will, therefore, continue further rearwardly past the catch 85, by depressing it against the action of the plunger 91, until the catch shoulder 72 passes the rear edge 96 of the top portion 86 of the catch 85, whereupon the latter will snap in front of the catch shoulder 72 and prevent a return forward movement of the bolt 40. When the trigger 73 is released it will be swung forwardly by the plunger 81, whereby the sear hook 78 will snap in front of the sear shoulder 71. During this forward swinging movement of the trigger 73 under the urge of the plunger 81, the front upper edge 94 of the catch 85 is engaged by the rearwardly facing shoulder 95 on the trigger 73 to swing the catch 85 with the trigger and release the catch 85 from the catch shoulder 72, as indicated in Figure 8. This will result in the bolt 40 moving slightly forwardly, whereby the sear hook 78 will engage the sear shoulder 71 and the action will again be placed in operative firing position. In order to insure this result, the spacing between the sear hook 78 and the rear edge 96 of the top portion 86 of the catch 85 is slightly greater than the spacing between the sear shoulder 71 and the catch shoulder 72 formed on the bolt 40.

Briefly, the operation of the firearm, embodying the features and principles of this invention as above described, is as follows, assuming that the parts of the action thereof are in the positions shown in Figure 6, but that no cartridge 23 is in the chamber 21, this being the normal position of the parts of the action when the firearm is not in use. To prepare the firearm for use, the knurled sleeve 65 is grasped and by it the bolt 40 may be retracted into either of two positions. If the firearm is not to be immediately fired but is to be carried loaded, the bolt 40 is fully retracted and the inner end 68 of the sleeve 65 is snapped into the circular enlargement 69 of the slot 58, as shown in Figure 10 and is indicated by dotted lines in Figure 9. This is the safety locked position, from which, the action can be readily unlocked by withdrawing the inner end 68 from the circular enlargement 69, whereupon the sear hook 78 will catch the bolt against the sear shoulder 71.

If the firearm is to be immediately used, the bolt 40 is retracted only sufficiently to permit the sear hook 78 to snap in front of the sear shoulder 71. When the bolt 40 is in either of these positions the loading platform 24 is free to be depressed against the tension of the spring 34 to dispose a cartridge 23 into the chamber 21 from the shallow groove 32 in its top surface. When depressed, as shown in dotted lines in Figure 5, the forward curved portion 33 of the groove 32 is substantially in alignment with the chamber 21 and the cartridge 23 is guided thereby as it is pushed into this chamber. After a cartridge 23 has been inserted into the chamber 21 the platform 24 is released whereupon it is swung upwardly by the spring 34 to close the opening 25 in the receiver 14. When the platform 24 is in position to close the opening 25, the spring end 30 is disposed in alignment with the primer head 42 of the cartridge and lies closely adjacent thereto to prevent the cartridge falling from the chamber 21.

When the trigger 73 is pulled, the sear hook 78 is released from the sear shoulder 71 and the bolt 40 is forced forwardly by the spring 51 to fire the cartridge. In its travel forwardly the bolt 40 rides under the platform 24 and its flat surface 49 slides along the flat undersurface 29

of the platform, whereupon the platform is securely pressed up and locked into the opening 25 to seal it closed. At the same time the spring end portion 36 is pressed upwardly out of the way 5 into the groove 31. When the cartridge is fired the recoil, acting upon the bolt 40, forces it backwardly into retracted position and at the same time the empty shell is ejected through the opening 48, see Figure 7. This action is substantially 10 instantaneous and most always takes place before the user's finger has released the trigger 73 and permitted the sear hook 78 to be disposed in sear shoulder, 71, engaging position. In such instances, the catch 85 engages the catch shoulder 72 to hold the bolt 40 in retracted position, as shown in Figure 7, until the trigger 73 is released. Release of the trigger 73 releases the catch 85 from the shoulder 72 and simultaneously disposes the sear hook 78 in position to engage 15 the sear shoulder 71, as illustrated in Figure 8. A new cartridge may now be inserted into the chamber 21 and the above sequence of automatic operations again started by pulling on the trigger finger piece 74.

25 While there has been shown and described herein, one form of an improved firearm, it is to be understood that the invention may be embodied in other forms without departing from the spirit or essential attributes thereof. It is 30 therefore desired that the present embodiment be considered in all respects as illustrative and not restrictive, and it will be further understood that each and every novel feature and combination thereof, present in, or possessed by, the improved firearm herein disclosed, forms a part of the invention included in this application.

What is claimed and new and for which it is desired to secure Letters Patent, is:

1. In a firearm, a tubular receiver having a 40 slot through its wall and extending axially thereof, a bolt slidable in said receiver and having forwardly directed catch shoulders in line with the slot in the receiver and being spaced apart axially thereof, a trigger member disposed in the 45 slot in the receiver and pivoted to the wall thereof, a forwardly directed extension on said trigger member and having a catch end adapted to catch on the forward shoulder on said bolt, a spring reacting between the rear portion of the trigger 50 member and the receiver to urge the extension toward the bolt, a rearwardly directed shoulder on said trigger member adjacent the receiver, a catch member pivoted to the trigger member below the receiver and having a forward edge 55 adapted to engage the shoulder thereon, spring means reacting between the catch member and the trigger member to urge the forward edge of the catch member toward the shoulder on the trigger member, and a rearwardly directed edge 60 on the catch member adapted to catch on the rearward shoulder on said bolt.

2. In a firearm, a tubular receiver having a slot through its wall and extending axially thereof, a bolt slidable in said receiver and having forwardly directed catch shoulders in line with the slot in the receiver and being spaced apart axially thereof, a trigger member disposed in the slot in the receiver and pivoted to the wall thereof, a forwardly directed extension on said trigger member and having a catch end adapted to catch on the forward shoulder on said bolt, a spring reacting between the rear portion of the trigger member and the receiver to urge the extension toward the bolt, a rearwardly directed shoulder on said trigger member adjacent the receiver, a catch member pivoted to the trigger member below the receiver and having a forward edge adapted to engage the shoulder thereon, spring means reacting between the catch member and the trigger member to urge the forward edge of the catch member toward the shoulder on the trigger member, and a rearwardly directed edge on the catch member adapted to catch on the rearward shoulder on said bolt.

70

receiver, a catch member inverted U-shaped in cross-section straddling said trigger member and being pivoted thereto below the receiver and having a forward edge adapted to engage the shoulder thereon, spring means reacting between the catch member and the trigger member to urge the forward edge of the catch member toward the shoulder on the trigger member, and a rearwardly directed edge on the catch member adapted to catch on the rearward shoulder on 10 said bolt.

3. In a firearm, a tubular receiver having a slot through its wall and extending axially thereof, a bolt slidable in said receiver and having forwardly directed catch shoulders in line with 15 the slot in the receiver and being spaced apart axially thereof, a trigger member disposed in the slot in the receiver and pivoted to the wall thereof, a forwardly directed extension on said trigger member and having a catch end adapted 20 to catch on the forward shoulder on said bolt,

a rearwardly directed portion on said trigger member extending under said receiver, a spring reacting between the rearwardly directed portion of the trigger member and the receiver to urge the extension toward the bolt, a rearwardly directed shoulder on said trigger member adjacent the receiver, a catch member inverted U-shaped in cross-section straddling said trigger member intermediate the trigger member extension and its rearwardly directed portion, and being pivoted thereto below the receiver and having a forward edge adapted to engage the shoulder thereon, spring means reacting between the catch member and the trigger member to urge the forward edge of the catch member toward the shoulder on the trigger member, a rearwardly directed edge on the catch member adapted to catch on the rearward shoulder on said bolt, and means to limit the upward movement of the trigger member extension toward said bolt.

HAROLD F. MOSSBERG.
